ATTORNEY

UNITED STATES PATENT OFFICE

90,677

DESIGN FOR AN X-RAY TILT TABLE

Albert C. Nelson, Flushing, N. Y., assignor to
Westinghouse X-Ray Company Inc., a corpora-
tion of Delaware

Application June 15, 1933. Serial No. 48,411

Term of patent 7 years

To all whom it may concern:

Be it known that I, ALBERT C. NELSON, a citizen
of the United States, residing in Flushing, in the
county of Queens and State of New York, have
invented a new, original, and ornamental Design
for an X-Ray Tilt Table, of which the following
is a specification, reference being had to the
accompanying drawing, forming part thereof.

The figure is a perspective view of an X-ray
tilt table showing my new design.

I claim:

The ornamental design for an X-ray tilt table
as shown.

ALBERT C. NELSON.
